DESIGN FOR A COLPOSCOPE OR AN ANALOGOUS ARTICLE

Harry O. Maryan, Chicago, Ill.

Application February 19, 1935, Serial No. 55,497

Term of patent 7 years

To all whom it may concern:

Be it known that I, Harry O. Maryan, a citizen of the United States, residing at Chicago, in the county of Cook and State of Illinois, have invented a new, original and ornamental Design for a Colposcope or an Analogous Article, of which the following is a specification, reference being had to the accompanying drawing, forming a part thereof.

In the drawing:

Fig. 1 is a side elevational view of a colposcope showing my new design; and

Figs. 2, 3 and 4 are, respectively, a side elevational view, a front elevational view, and a top plan view, on a somewhat enlarged scale, of the top part of the complete colposcope shown in Fig. 1, the representation of the electric cord being omitted from Figs 3 and 4.

What I claim is:

The ornamental design for a colposcope or an analogous article substantially as shown and described.

HARRY O. MARYAN.
